(57) **CLAIM**

The ornamental design for rack connector, as shown and described.

DESCRIPTION

FIG. 1 is a front perspective view of rack connector showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is a perspective view showing the design of the present invention, where those elements indicated by broken lines are not claimed.

The broken lines shown in the drawings are included for the purpose of illustrating environmental structure and form no part of the claimed design.
